UNITED STATES PATENT OFFICE

2,546,449

GARBAGE CAN AND RACK

John B. Herdy, San Antonio, Tex.

Application November 8, 1946, Serial No. 708,736

9 Claims. (Cl. 248—147)

1

This invention relates to a refuse receptacle holder or rack embodying useful and novel improvements over prior inventions of this type.

An object of this invention is to provide novel means for lifting and closing the receptacle cover.

Another object of this invention is to provide new and improved latching means for holding the receptacle cover in an opened position.

A further object of this invention is the provision of a receptacle cover which cannot be misplaced or removed by animals.

A still further object of this invention resides in the provision of an inexpensive and practical device which lends well to manufacture.

Another object of this invention is to provide a receptacle retaining means which holds the said receptacle in such a manner as to be extremely accessible and easy to empty.

Other objects and features of novelty of this invention will be specifically pointed out or will become apparent when referring, for a better understanding of my invention, to the following description taken in conjunction with the accompanying drawings, wherein:

Figure 1 is a side elevational view of the instant invention.

Figure 2 is a plan view of Figure 1.

Figure 3 is a sectional view taken on the line 3—3 of Figure 1 and in the direction of the arrows.

Figure 4 is an enlarged detail of an adjustable bearing and latching means forming part of this invention.

Figure 5 is a detail of Figure 4 and taken on the line 5—5 of the same in the direction of the arrows.

Figure 6 is a detail similar to Figure 5 taken on the line 6—6 of Figure 4 and in the direction of the arrows.

Figure 7 is a fragmentary elevational detail of construction showing particularly the latching means forming part of the present invention.

Referring now to the drawings more in detail wherein like reference characters indicate similar parts throughout the views of the invention, the reference numeral 10 indicates generally the invention.

A vertical post 12, adapted to be fixed permanently is provided and forms an anchorage for the invention. Received on the said post is a slidably adjustable bearing and latch member 14 secured by suitable locking means such as the set screw 16 illustrated in the drawings. A pair of ring bearings or collars 18 and 20 are rotatably secured on the said post 12 and are fixed in sep-

2

arated relation by a link or arm member 22 secured thereto by some suitable means such as welding, brazing or the like. Secured to the lower end of arm 22 and the bearing 18 is a pair of arms 5 or links 24 and 26 which have a U shaped member or bracket rigidly secured to the ends thereof for engaging a refuse receptacle 27 and abuts an appropriate ring 30 of the same inner diameter as the said U member. It is here noted that the links 24 and 26 cooperating with member 28 form substantially a pair of bifurcated arms (see Figure 3) starting from the bearing 14 and following each arm around to its termination at the farthest point of the refuse receptacle 27. For convenience the above discussed members shall be referred to as bifurcated arms or links.

Secured to the upper ring bearing or collar 20 and upper end of the rod 22 are a pair of links 32 and 34 whose opposite ends are rigidly fixed 20 to the said bifurcated arms by some suitable conventional means such as welding or the like.

Received in an aperture in the said bifurcated arms is a pin 36 which pivotally secures latch 38 thereto. The bottom end of the said latch has 25 an arcuate plate 40 fixed thereto adapted to engage the side of the receptacle 27. The top end of the latch 38 is notched at 42 to receive a latch keeper to be discussed hereinafter. Between the pivot and the top of latch 38 is an aperture for 30 receiving a biasing spring 44 the other end of which is secured to the link 22.

Secured to links 32 and 34 by suitable means such as bolts 46 and 48 or the like is a stub shaft or pivot pin 50. Journaled on the said stub shaft is a pair of bearings 52 and 54 limited in endwise travel by retainers 56 and 58. A latch keeper 60 is secured to both of the said bearings and is adapted to engage the latch 38 in the notch 42. Welded or fixed by some equivalent means to 40 the bearings 52 and 54 and the latch keeper 60 is a pair of actuators or arms 62 and 64 with a suitable handle 65 thereon. Permanently fixed to the bottom of the said actuators is a refuse can cover 66.

45 The operation of the above described is self evident from an inspection of Figure 1. Handle 65 is lifted carrying receptacle cover 66 in an arcuate travel and off the receptacle 27; thence it is latched in an upwardly tilted position as 50 spring biased latch 38 is pulled under the keeper 60.

Referring now more specifically to Figures 5 and 6 wherein the bearing and latch member is shown, a housing 68 is provided with a screw 55 threaded plug 70 closing the bottom end thereof,

In the said housing is a spring 72 loading a piston 74 and biasing it outwardly of said housing and plug. The piston or pin 74 is adapted to engage a portion of the aperture between the said bifurcated arms as shown best in Figures 1 and 4. A conventional slot 75 and limiting pin 76 arrangement is provided in the housing for limiting the travel of the pin 74 and for actuation of the same.

In viewing Figure 1 it is evident that the entire invention could be revolved around the anchorage 12 to any desired position and it is also evident that the invention could be adjusted on the pole 12 to suit varying sized receptacles. Also contemplated by this invention is the provision for more than one of the illustrated embodiments of this invention to be secured to a single anchorage member 12 having each mechanism oppositely disposed.

While there is described and illustrated the preferred embodiment of the instant invention, it will be apparent to those skilled in the art that various changes including omissions and additions may be made herein without departing from the spirit and scope of this invention as set forth in the accompanying claims.

Having thus described this invention, what is claimed is as follows:

1. In a device of the character described, a vertical anchoring post, a bearing and keeper member adjustably secured to said post, a pair of fixedly spaced collars on said post one of which engages said member, a pair of bifurcated arms secured to one of said collars and adapted to engage a refuse receptacle, a pair of arms secured to the other of said collars at one end thereof and secured to said bifurcated arms at the other end thereof, a latch pivotally mounted between said pair of bifurcated arms, a stub shaft mounted between said pair of arms, a latch keeper pivotally secured to said stub shaft, a pair of actuating rods having a refuse receptacle cover thereon and fixedly secured to said latch keeper, whereby the said actuating rods may be lifted and latched in a predetermined position.

2. A refuse receiving apparatus comprising an anchoring post having a bearing thereon, an upper and lower collar journaled on said post, said lower collar being seated on said bearing, means for maintaining said collars in fixed spaced relation, a link secured to said lower collar, a bracket secured to said link for engaging the side of a refuse receptacle, a pair of spaced arms secured to said upper collar and to said bracket, a latch pivotally secured to said link, means for raising and lowering a refuse receptacle cover pivoted between said arms, and means associated with said raising and lowering means and said latch for maintaining said raising and lowering means in a predetermined position.

3. The combination of claim 2 and resilient means for constantly biasing said latch.

4. The combination of claim 3, said resilient means comprising a spring attached to said spacing means and said pivoted latch.

5. The combination of claim 4 and means attached to said bearing for locking said link for preventing relative rotation between said post and said link.

6. The combination of claim 5 and means for locking said bearing in selected positions on said post.

7. In a refuse receiving apparatus, an anchoring post, a bearing secured to said post, a link, journaled means attached to said link and seated on said bearing, a bracket attached to said link adapted to engage a refuse receptacle, a latch pivoted to said link, means for raising a refuse receptacle cover and maintaining the cover in the raised position, means secured to said latch for releasing the cover raising means and arranged to be actuated by engagement with the refuse receptacle, means for resiliently opposing the operation of said latch, and means attached to said bearing for maintaining said link in selected positions of rotation.

8. In a refuse receiving apparatus, an anchoring post, a bearing secured to said post, a link, journal means attached to said link and seated on said bearing, a bracket attached to said link adapted to engage a refuse receptacle, a latch pivoted to said link, means for raising a refuse receptacle cover and maintaining the cover in a raised position, means secured to said latch for releasing the cover raising means and adapted to be actuated by engagement with a refuse receptacle, a pair of spaced arms, means for journaling said arms on said post, said arms being attached to said bracket, said cover raising and maintaining means including a shaft journaled in said arms, a keeper secured to said shaft, and actuator arms secured to said shaft, and said latch having a notch for seating said keeper at selected rotated positions of said actuated arms.

9. The combination of claim 8 and means for resiliently biasing said latch to maintain said keeper in said notch until said latch releasing means is actuated.

JOHN B. HERDY.
